UNITED STATES PATENT OFFICE.

GILBERT S. WALKER, OF WASHINGTON, DISTRICT OF COLUMBIA.

AUTOMATIC WATER HEATER.

Application filed July 17, 1918. Serial No. 245,280.

To all whom it may concern:

Be it known that I, GILBERT S. WALKER, a citizen of the United States, residing at Washington, in the District of Columbia 5 (whose post-office address is American Society of Mechanical Engineers, 29 West 39th Street, New York, N. Y.), have invented a new and useful Improvement in Automatic Water Heaters, of which the following is a specification.

My invention relates to improvements in automatic water heaters.

The primary object of my invention is to produce a device whereby the flow of water 15 is automatically regulated by the thermostat, and also to control the flow of gas to the burners in a simple manner.

One of the advantages of my invention is economy in the consumption not only of gas 20 but also of water. An additional advantage is that the friction of the water through the heater is utilized in operating the piston, thus reducing the loss of head when water is drawn on the top floor.

25 In the accompanying drawings, Figures 1, 4, 5 and 6, I show the preferred form of my invention. In Figures 2 and 3 I show some of the parts in modified form.

Figure 1 is a side elevation of a well 30 known style of water heater with my invention applied.

Figure 2 is a front view of a modified form of the invention, the parts being shown in section.

35 Figure 3 is a side view of the same, the coils and burners being shown diagrammatically.

Figure 4 is a top view of the preferred form.

40 Figure 5 is a vertical section through the water motor and gas valve of the same form.

Figure 6 is a vertical section through the thermostat and water valve of the same form of the invention.

45 Referring to Fig. 1 the numeral 1 indicates the shell or casing of the heater, 2 is the usual coil located within said shell, 3 is the usual burner or burners located immediately below said coil for heating the water, 4 is a thermostat preferably placed in

50 the outlet of the lower section of the coil

and may be of any of the usual types of construction.

The flow of water through the heater is from a cold water inlet pipe 5, to a water 55 valve 6 where the quantity of water is regulated by the thermostat, then through a pipe 19 to the coil where the water is heated, then through the thermostat, and through a pipe 18 to one of the outlet faucets HWO. 60 There are also small water pipes 15 and 83 communicating from the water on the two sides of the water valve 6 to corresponding sides of a water motor 9, so that when there is a difference of water pressure due to the 65 restriction of the water flow by valve 6, the water motor will move and open a gas valve 36.

Gas enters from a gas inlet pipe 39, flows 70 through gas valve 36 and a pipe 41 to the burners 3. There is also a small gas pipe 43 conducting gas through a small valve 44 to a pilot burner 45, which serves to ignite the main burners 3.

There is a frame 22 holding the various 75 parts in place.

In Figs. 2 and 3 I show a modified form of my invention. The heating coil is shown at 2' and the burners at 3'. The thermostat T shown at the left of Fig. 2 is of a well 80 known type in which a copper pipe 4' forms a part of the conduit for the hot water as it passes from the coil 62' to the hot water outlet pipe 18'. A part of the cold water pipe 19' forms the frame of the thermostat. 85 These pipes are held firmly together at the top by the casing of the check valve 50' and at the bottom of the thermostat the cold water pipe 19' is held firmly at 51' to the main frame 22'. The small pipe 15' being 90 flexible, the lower part of the copper pipe 4' is free to move up and down under the influence of the temperature of the hot water. A knife edge 52' attached to the copper tube transmits movement to the lever 24'. This 95 lever 24' fulcrums on the point of the screw 25' carried by the frame 22'. The further end of the long arm of this lever transmits the movement to the water valve stem 10'.

On the upper end of the valve stem 10' 100 is a knife edge 31' on which the lever 24' rests. Adjustments are provided so that the

water valve may be set to close when the temperature falls below a predetermined point. The water valve stem passes through the stuffing box 13' into the upper chamber 5 of the valve casing 6' and is fastened to the two valves 7' and 7^a, said valves being adapted to close on the two seats 8' and 8^a. These valves are urged to their seats by the spring 54' and, considered together, are in 10 approximate hydrostatic balance. The stem 10' is made as small in diameter as practicable.

The gas valve 36' is urged to its seat 37' by the spring 38'. This spring urges the 15 water motor or piston 9' down to the normal position shown. The piston 9' is accurately fitted in its cylinder 59' and may be provided with soft packing at the top to reduce the leakage. The bottom of the 20 cylinder is in communication with the cold water inlet pipe 5', and the top may be put in communication with either the cold water pipe 19' beyond the valve 7', or with the hot water outlet pipe 18'. The change 25 is effected by a small three-way cock 63'. In either case the communication is through the opening 14' and the pipe 15', and the speed of the movement of the piston is controlled by the small valve 16'. The cylinder 30 59' is provided with a port 60' adapted to be uncovered by the bottom of the piston 9' when the adjustment of the screw 47' permits, so that, if desired, some water will flow as soon as a faucet is opened, even 35 though this first flow of water may not be hot. The amount of water that will flow at such time can be regulated by either the conversion cock 61' or by the adjusting screw 47'. The opening of the gas 40 valve can be made sufficient for either case. I prefer, however, to close the conversion cock 61' and allow the thermostat to regulate the quantity of water flowing through 45 the heater, all the way from no flow (except that due to leakage) when cold, to full free flow of water when hot.

One of the well known circulating systems is provided for conducting hot water to the thermostat when no water is flowing 50 from the heater. It consists of a reversed bottom section 62' of the heating coil and a ball check valve 50', the latter to prevent cold water from the pipe 19' passing into the hot water pipe 18'. When brought 55 into operation by the opening of a hot water faucet the back pressure on the top of the piston 9' is reduced and the piston rises as fast as the water can escape through the small valve 16'. This opens the gas 60 valve 36', and the gas flows to the burners 3' where it is ignited by the pilot burner 45'. As the water in the lower section of the coil gets hot it rises into the thermostat 4', lifts the check valve 50' allowing 65 the colder water to pass from the

top of 4' into the pipe 19', and down through the coil 2' and return to the lower section 62'. The thermostat when thus heated or when heated directly as in the first described form of the invention, opens 70 the water valves 7' and 7^a, and allows cold water to flow in from the inlet pipe 5', up through the pipe 19', and as it can not pass down through the check valve 50', it is compelled to pass down through 75 the coils 2' and 62' where it is heated and passes on through the thermostat 4' to the hot water outlet 18'. As long as water is drawn, the thermostat will move the water valve up and down enough to regulate 80 the flow of water and proportion it to the amount of heat supplied by the burners, and so furnish hot water at a practically uniform temperature, regardless of changing conditions. If the water gets too hot, the valve 7' will be opened 85 far enough to reduce the difference of pressure on the two sides of the piston 9' sufficiently to let the spring 38' close the gas valve 36'. As previously stated, the conversion cock 61' may be opened to permit 90 any desired amount of water to flow through the heater before it is hot. If the cock 61' is fully opened the device will then regulate the gas supply, leaving the 95 water flow nearly uniform.

It will be understood that the circulating system and thermostat shown in Figs. 2 and 3 can be interchanged with those shown in the other figures.

In Figs. 4 to 6 I show the preferred form of my invention, in which the thermostat is shown at 4''. It is so constructed that when the copper tube 21'' expands under the influence of heat it permits the porcelain rod 23'' to move to the left under the action of the spring 70'' transmitted by the compound levers 24'' and 26''. The spring 70'' is strong enough to overcome the spring 54'' and the friction and keep the thermostat and its levers under a continuous stress. The thermostat is made unusually heavy because the thermostats familiar in this art operate gas valves, and a water valve cannot be made to operate as easily as a gas 115 valve. On the lower end of the water valve stem 10'' is a knife edge 31'' bearing on the under side of the lever 26'' and adjustable so the water valve can be set to open when the water reaches the predetermined temperature. The stem 10'' is very small in diameter so as not to unbalance the valve too much. The stem passes through a stuffing box 13'' and is connected to lugs attached to the valve 7''. Attached 120 to the upper side of the valve is a piston 71'' of nearly the same area as the valve. The relative areas of the valve and its piston may be varied slightly so as to get the valve as nearly balanced as possible so 125 130

it can be moved in either direction with the minimum force. A water passage 72" puts the water below the valve 7" in communication with the water above the piston 51" and permits the pressures to equalize so that the valve will operate independently of water pressures. A spring 54" closes the valve when the thermostat is cool enough to permit.

10 The water enters at 5" passes through the valve 7" and pipe 19" to the top of the heater coil.

The gas enters at 39", passes through a gas valve 36" and through a pipe 41" to the burners. The valve 36" is urged to its seat 37" by a spring 38" and by gravity. These forces also deflect a diaphragm 80" until the gas valve is seated. The lower chamber 82" of the water motor 9" is supplied with water at inlet pressure through the pipe 83" which communicates with the inlet pipe 5". The chamber above the diaphragm communicates with the hot water pipe by means of pipe 14", cock 16", pipe 20 15" and pipe 19". There will generally be sufficient leakage past the valve 7" to equalize the pressure on the two sides of the diaphragm and supply the water which leaks out of the house fixtures, but if not 25 a small hole may be made at any convenient point for the purpose.

Figures 4, 5 and 6 show all the parts in their normal position as they are when no water is being drawn and the thermostat 35 has become cool. Upon the opening of any hot water faucet there will be a reduction of water pressure in the small pipe 15" and in the chamber 84". The diaphragm 80" will be forced upward by the water pressure 40 communicated from the inlet pipe 5" through pipe 83". This water pressure is not reduced materially by the opening of the faucet because the water flow is restricted by the water valve 7". When the diaphragm goes up it opens the gas valve 36" 45 fully.

Gas will now flow freely to the main burners and be ignited by the pilot light. Combustion at maximum efficiency will take 50 place because the gas flow is normal and the burners are made and adjusted for this flow. The thermostat still being cool, water valve 7" remains closed and little or no water flows from the faucet. Consequently 55 the water is heated quicker than would otherwise be the case and there is a saving of both gas and water. Furthermore, the flow of water from the faucet informs the user as to the operation of the heater.

60 As the temperature of the water approaches the predetermined temperature, the inner thermostat tube 21" expands, and the porcelain rod 23", whose length is changed but little by heat, moves slightly to the left. 65 This movement is multiplied by the com-

pound levers so that the right end of lever 26" lowers rapidly. At the predetermined temperature the water valve 7" will open slightly so that a small amount of water will flow from the faucet.

If the temperature of the water increases beyond the predetermined point the water valve will open farther, and if the temperature falls below the predetermined point the water valve will close somewhat. Thus the 75 water will be delivered at practically uniform temperature, the quantity of water being automatically varied in accordance with the amount of heat produced by the burners. Meanwhile the burners continue to burn at 80 their full capacity and greatest efficiency, which is not the case with the usual kind of automatic water heater.

In the unusual event of the faucet being opened only part way, or if for any other reason the water does not carry away the heat as fast as it is produced, the water valve will open so far that the pressures on the two sides of the diaphragm will be equalized and the spring will close the gas valve.

At any time during the above described operation that the faucet is closed, the pressures on the two sides of the water motor immediately equalize, allowing the spring to close the gas valve.

I claim as my invention and desire to secure by Letters Patent:—

1. In an automatic water heater, a casing, a water conduit within the casing, a burner for heating the water conduit, means for automatically bringing the burner into action when the outlet of the heater is opened, a thermostat responsive to the temperature of the water within the conduit, a water valve completely controlling the flow of water through the conduit, and an operative connection between the thermostat and the water valve whereby the water valve is actuated automatically according to the temperature of the water within the conduit and independent of water pressures.

2. In an automatic water heater, a water heating coil having a water inlet and a water outlet, a burner for heating the coil, means for automatically bringing the burner into action when the water outlet is opened, a balanced water valve completely controlling the flow of water through the heating coil, a thermostat in the coil, and an operative connection between the thermostat and the balanced water valve whereby the said valve is automatically actuated to control the flow of water through the heating coil according to the temperature of the water within the heating coil.

3. In an automatic water heater, a conduit having an inlet and an outlet, a burner for heating the conduit, means for automatically bringing the burner into action when the outlet of the conduit is opened, a normally

- closed water valve completely controlling the flow of water through the conduit, a thermostat within the conduit, and an operative connection between the thermostat and the water valve whereby the water valve is opened and closed according to variations of temperature of the water in the conduit.
4. In an automatic water heater, a heating coil having an inlet and an outlet, a burner for heating the coil, means for automatically supplying fuel to the burner when the outlet is opened, a thermostat in the coil, a normally closed balanced water valve completely controlling the flow of water through the coil, a thermostat responsive to the temperature of the water within the coil, and an operative connection between the thermostat and the water valve whereby the said valve is automatically opened and closed according to the temperature of the water in the heating coil.
5. In an automatic water heater, a water conduit having an inlet and an outlet, heating means for the conduit, a water valve completely controlling the flow of water through the conduit, a thermostat responsive to the heat of the water within the conduit, an operative connection between the thermostat and the water valve for automatically moving the water valve to regulate the flow of water through the conduit in accordance with the temperature of the water, a water motor independent of the water valve, and means actuated by the water motor for controlling the heating means.
6. In an automatic water heater, a gas burner, a gas valve, a water pipe, a water valve completely controlling the flow of water through the pipe, a thermostat in the heat zone of the gas burner, an operative connection between the thermostat and the water valve whereby the water valve is actuated altogether by the thermostat and the temperature of the water is regulated by varying the flow of water through the heater, and means for automatically operating the gas valve by differences of pressure on opposite sides of the water valve.
7. In an automatic water heater, a gas burner, a gas valve to regulate the burner, a water motor having an inlet chamber and an outlet chamber, means operatively connecting the water motor to the gas valve, a water pipe, a water valve in the water pipe controlling the flow of water through the heater, means establishing communication between the water pipe on the inlet side of the water valve and the inlet chamber of the water motor, means establishing communication between the water pipe on the outlet side of the water valve and the outlet chamber of the water motor, a thermostat in the heat zone of the gas

burner, and means operatively connecting the water valve to the thermostat.

8. In an automatic water heater, a manually controlled outlet valve for the heater, a normally closed automatic water valve completely controlling the flow of water through the heater when the outlet valve is opened, a thermostat responsive to the temperature of the water within the heater, an operative connection between the thermostat and the automatic water valve, whereby the said water valve is automatically opened and closed according to the temperature of the water within the heater and the temperature of the water withdrawn from the heater is regulated by varying the quantity of water permitted by the automatic water valve to flow through the heater, a burner, and means actuated by differences of pressure on opposite sides of the automatic water valve for automatically turning the burner on and off.

9. In an automatic water heater, the combination with a heating conduit, heating means for the conduit, a manually controlled outlet valve for the conduit, automatic means for completely controlling the flow of water through the heater according to the temperature of the water when the outlet valve is opened and regulating the temperature of the water withdrawn from the heater by varying the quantity of water permitted to pass through the outlet, and means actuated automatically by the opening and closing of the outlet valve for automatically rendering the heating means operative and inoperative.

10. In an automatic water heater, a normally closed water valve completely controlling the flow of water through the heater, a thermostat responsive to the temperature of the water within the heater, an operative connection between the thermostat and the water valve for opening and closing the water valve automatically according to the temperature of the water within the heater, and governing the temperature by varying the quantity of water permitted by the valve to pass through the heater, a gas burner, a normally closed gas valve and a water motor actuated by differences of pressure on opposite sides of the water valve for automatically controlling the gas valve whereby the gas valve will be closed when there is no flow of water through the heater and also when the water valve is fully opened, so that there is no difference in the pressures on opposite sides thereof.

Signed at Washington, in the District of Columbia, this 16th day of July, 1918.
